UNITED STATES PATENT OFFICE.

CARL JACOB AMANDUS HANSSEN, OF CHRISTIANIA, NORWAY, ASSIGNOR TO AXEL WINGE,
OF CHRISTIANIA, NORWAY.

BALCONY FIRE-ESCAPE.

No. 882,677.

Specification of Letters Patent. Patented March 24, 1908.

Application filed September 17, 1907. Serial No. 393,834.

To all whom it may concern:

Be it known that I, CARL JACOB AMANDUS HANSSEN, architect, a citizen of the Kingdom of Norway, residing at Camilla Colletts Vei 5 10, in the city of Christiania, Norway, have invented a new and useful Improvement in Balcony Fire-Escapes; and I do hereby declare the following to be a full, clear, and exact description of the same.

10 The sliding balcony fire-escapes hitherto constructed, which can be raised and lowered outside the house wall by the persons in the balcony, have not been practical in construction. An unproportionably great 15 exertion of power is required for raising the device, and the raising takes too long a time. The device therefore has not been suitable to the purpose. Further the moving mechanisms are very complicated; they easily get 20 out of order and enhance the price of the apparatus.

My present invention has now for its object to provide a balcony fire-escape which is distinguished by a simple and reliable construction of the moving mechanism by which 25 the apparatus may easily be lowered as well as raised. Furthermore the arrangement—contrary to prior constructions of similar kind—is such, that the balcony, which in 30 resting position is situated uppermost beneath the roof above a vertical row of windows, can be lowered from and moved on to each of said windows.

The invention is illustrated in the accompanying drawing, in which:—

Figure 1 is an elevation of the balcony arranged outside a vertical row of windows, Fig. 2 is a vertical cross section showing the whole moving mechanism, and Fig. 3 is a 40 plan view partly in section.

The balcony proper —1— is preferably made as a basket with bottom of sheet metal and sides of net of metal wire. In the four corners turning against the wall lugs —2— 45 are provided. Said lugs surround pairwise two vertical steering cables —3— of wire-rope. The cables —3— prevent dangling of the balcony and hold the same out from contact with the wall. The balcony is carried 50 by two ropes —4— passing around two rollers —6— and through holes —7— in the wall in to the loft in order to be coiled upon two drums —8—. The rollers —6— are carried by brackets —5— attached outside 55 the wall. The drums —8— are keyed on a

common shaft —9— supported in bearings —10— and provided at one end with a worm wheel —11— meshing with a worm —12— keyed on a horizontal driving shaft —13—, one end of which passes out through the wall 60 and carries outside the same a chain wheel —14—. Around the latter is placed an endless chain —15— hanging down at one side of the window-row so that it may be reached from each of the windows. 65

If one or the other chain part is pulled, the balcony is raised or lowered. By this arrangement the great advantage is obtained that the balcony may be moved on from each window in the row, because the 70 hand-driving part (here the chain) is not as hitherto arranged on the balcony itself so as to be reachable only from the same, but said part is arranged in such a manner, that it may be reached and operated from the 75 balcony as well as from each of the windows in the row. Only hereby the apparatus may be fully utilized.

Experience has shown, that a balcony provided with the moving mechanism above 80 described may be lowered and raised along the wall without worth-mentioning exertion of power.

Having now described my invention, what I claim as new and desire to secure by Letters Patent is:—

In a sliding balcony fire-escape the combination of a balcony arranged outside a vertical row of windows, ropes carrying the balcony, drums keyed on the same shaft and 90 around which said ropes are coiled up, said drums being preferably arranged in the loft of the house, a worm wheel keyed on said shaft, a worm meshing with the worm wheel and being keyed on a horizontal shaft projecting out through the wall, a chain wheel 95 keyed on the outer end of the last-mentioned shaft and a driving chain passing around the chain wheel and hanging down at one side of the window row so that it may be reached and operated both from the balcony and from each of the windows. 100

In testimony whereof, I have signed my name to this specification in the presence of two subscribing witnesses.

CARL JACOB AMANDUS HANSSEN.
